CLAIM

The ornamental design for an outboard engine for ships as shown and described.

DESCRIPTION

4. Outboard Engine for Ships

9. Outboard Engine for Ships

4.1 : Perspective

4.2 : Perspective

4.3 : Front

4.4 : Back

4.5 : Left

4.6 : Right

4.7 : Top

4.8 : Bottom

9.1 : Perspective

9.2 : Perspective

9.3 : Front

9.4 : Back

9.5 : Left

9.6 : Right

9.7 : Top

9.8 : Bottom

(Continued)

The broken lines in the drawings illustrate portions of the outboard engine for ships that form no part of the claimed designs.

1 Claim, 16 Drawing Sheets
